UNITED STATES PATENT OFFICE

FRANK E. FOWLER, OF ATHENS, GEORGIA

PRINTING MACHINE

Application filed November 19, 1930. Serial No. 496,759.

This invention relates to a machine for stenciling or printing crates, boxes, bottle cases and the like, the general object of the invention being to provide a roller having thereon the printing type with means for rotating the roller as it is moved bodily along a support and means for applying paint, ink, or the like to the type as the roller is moved along a part of the device after which the roller moves over the crate to print the same.

Another object of the invention is to provide means whereby the proper amount of paint or the like is placed on the type.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is an elevation of the invention.
Figure 2 is a view of one end thereof.
Figure 3 is a view of the other end.
Figure 4 is a top plan view.

Figure 5 is a fragmentary sectional view showing the brush supporting means, the tank and the dipper.

Figure 6 is a section on the line 6—6 of Figure 4.

In these views the numeral 1 indicates the base and the numeral 2 indicates an upright fastened at its lower end to each end of the base. The uprights are connected together intermediate their ends by a member 3. A crosspiece 4 is connected to the upper end of each upright and the pair of guide bars 5 are each rotatably connected at one end to one of the crosspieces as shown at 6. The other end of each guide bar passes through a U-bolt 7 passing through the other crosspiece and having springs 8 on the limbs below the crosspiece to yieldingly hold the guide bars against the crosspiece.

A tubular member 9 is slidably arranged on each guide bar and a crosspiece 10 connects the two tubular members together. A

hollow shaft 11 is rotatably arranged on the crosspiece 10 and carries a printing roller 12 and a drum 13. The type is formed on a member 14 of resilient material which encircles the printing roller and the circular pad 15 is placed between the roller and the member 14. The member 14 has its ends detachably connected together so that it can be readily removed and another member substituted therefor whenever necessary or desirable. The drum 13 is formed with a spiral groove 16 in its circumference which is engaged by a cable 17, one end of which is adjustably connected with the crosspiece 4 as shown at 18 and the other end of which is adjustably connected with the bent extended end 19 of one of the bars 5.

A brush supporting bracket 20 is clamped to a crosspiece 21 which has its ends connected with the tubular members 22 which are also slidably arranged on the bars 5. The brush 23 is fastened to the bracket by a bolt 24 which passes through the handle of the brush and through a slot 25 in the top part of the bracket.

An elongated pan 26 is suitably supported in the frame adjacent one end thereof and one end of the pan extends slightly into a tank 27 which contains the ink, paint, or the like with which the crate or case is to be printed.

A dipper 28 formed of a perforated plate of slightly curved construction is placed in the tank and its handle 29 is connected to one edge of the dipper, said handle being pivotally connected with the tank as shown at 30 and a spring 31 connects the upper end of the handle with the projection 32 of the frame so that the dipper is held with its central part substantially at the liquid level of the tank. A chain 33 connects the upper end of the handle with the bracket 20 and when the bracket has been moved a certain distance away from the tank the chain will be tightened so that the handle is tilted and thus the dipper will enter the liquid in the tank. As the chain is slackened the spring 31 will return the dipper to its normal position and surplus liquid will flow from the dipper through the perforations back into the tank. Thus, only a small amount of the liquid will adhere to the

bristles of the brush as said bristles move over the perforated plate of the dipper. As the brush leaves the dipper it will come in contact with the projecting edge of the pan which 5 acts to scrape off some of the liquid from the front edge of the brush before the brush moves over the bottom of the pan, but on the return movement of the brush the rear portion of the bristles thereof will engage the 10 bottom of the pan to place more of the liquid on said bottom.

Levers 34 and 35 have their lower ends pivotally connected with the base and the upper end of the lever 34 is connected with one of 15 the tubular members 22 by a pin 35' engaging the slot 36 in the lever and the pin 37 on one of the tubular members 9 engages a slot 38 in the upper end of the lever 35. The lower portions of the two levers are connected together 20 by a link 39 and the lever 35 is connected by link 40 with the crank 41 carried by a shaft 42 journaled in part of the frame. Worm gearing 43 connect the shaft 42 with the shaft 44 which is driven from a motor M or the 25 like.

An upright 45 has its lower end fastened to the member 3 and angle arms 46 are connected with the top of the upright 45 so that the 30 crate or box A will be supported by placing it on these arms 46 as shown in Figure 1. The upright 45 and its arms will hold the crate in a position where one side of the crate will be acted on by the printing roller.

The parts are so arranged that the lever 34 35 and the brush carrying parts will move much slower than will the lever 35 and the printing roller and drum, and the parts are so timed in the movement that the brush lever 34 only moves about half the distance of the lever 40 35, the latter lever moving practically the entire length of the machine. The brush only moves at about half the speed as that of the printing roller. As the parts move to the left in Figure 1, the brush passes over the pan 45 and then enters the dipper which has been raised by the spring 31. During the forward and backward movement of the brush over the pan the brush will apply a coating of the printing liquid to the bottom of the pan so 50 that as the printing roller passes over the pan the type will be coated with the liquid. As the parts move in an opposite direction or to the right in Figure 1, the printing roller will leave the pan and roll over the upper 55 side of the crate so as to print the same and the brush will move over the pan to give the bottom of the pan another coating.

The cable 17 causes the drum, the hollow shaft 11 and the printing roller 12 to rotate 60 as the lever 35 is oscillated and this positive means of rotating the printing roller will prevent blurring of the matter printed on the crate.

The printing roller moves beyond the end 65 of the case or crate after printing so that the

operator can remove the crate and turn the other side up and replace it on the arms and while he is turning the crate or case the parts will move rearwardly so that the printing roller will roll over the pan and again have the type thereon coated with the liquid. Then the parts move forward again to print the other side of the case or crate. The back and forth movement of the parts is continuous and the speed at which the parts move 70 can be regulated to suit the operator. The printing stroke of the printing roller causes the type thereon to pass back over the same places on the bottom of the pan which they contacted on the rearward stroke so that some of the liquid on the type is put back on the pan thus eliminating any possibility of the type retaining too much liquid. 75

By placing a pad under the type member of the printing roller and providing means whereby the guide bars 5 can move upwardly at the front ends the device can be used to stencil cases which are warped as such means will permit the type to contact the warped sides at all points and thus print the 80 same. 85

The usual way of applying wording on the sides of cases at the bottling plants is to use a stencil and stencil brush. This method is very slow and unless one is very careful the letters will not be formed clear and distinct. To stencil the average case requires something over one minute time. The printing machine is automatic in operation and any kind of paint, ink or enamel can be used to 90 print with. By using enamel paint for printing, the letters stand out better and show a high gloss which is very desirable on bottle cases that have been painted with a gloss paint. It is not possible to use enamel paint when the stencil and brush method is used. By using a gloss paint to paint case with and a gloss paint to print letters on sides of case, the case has the appearance of being varnished and to get this same appearance with 95 the stencil method, the case would have to be varnished which of course is additional expense and time. The uniform printing on every case, such as clear cut letters and uniform color of letters is another important feature that is very hard to get with stencil work. One man can do the work of several men with this machine, as the machine will print several cases per minute and he only has to put the cases on the machine and take it off after same has been printed. This saving of time is very important, as well as saving in labor. By changing the rubber die on die drum, any kind of lettering can be 100 105 110 115 120 125 130 printed on a case.

It is to be understood that changes may be made in the construction and in the combination and arrangement of the several parts, provided that such changes fall within the scope of the appended claims.

What I claim is:

1. A device of the class described comprising a supporting frame, a channel shaped pan supported by the frame, a tank at one end of the pan, a brush slidably supported in the frame and entering the tank at the end of its rearward movement and passing from the tank over the pan to apply liquid to the bottom of the pan, a printing roller slidably supported in the frame and moving over the pan at the rear part of its backward movement and at the forward part of its forward movement, means for sliding the brush carrying member and the printing roller, means for rotating the roller during its sliding movement, and means for supporting an object to be printed in the frame where it will be contacted by the printing roller after the same leaves the pan.
2. A device of the class described comprising a supporting frame including guiding means, a pair of members slidably arranged on the guiding means, a printing roller rotatably supported by one of said members, a brush supported by the other member, means for reciprocating the sliding members, a pan over which the brush is moved during its sliding movement, a tank arranged at one end of the pan, a dipper in the tank and engaged by the brush, means for normally holding the dipper above the liquid level in the tank, means for lowering the dipper by the brush carrying means after the brush leaves the pan, said printing roller engaging the pan during the part of its movement, means for supporting an object to be printed in the path of the printing roller and means for rotating the roller during its reciprocatory movement.
3. A device of the class described comprising a supporting frame including guiding means, a pair of members slidably arranged on the guiding means, a printing roller rotatably supported by one of said members, a brush supported by the other member, means for reciprocating the sliding members, a pan over which the brush is moved during its sliding movement, a tank arranged at one end of the pan, a dipper in the tank and engaged by the brush, means for normally holding the dipper above the liquid level in the tank, means for lowering the dipper by the brush carrying means after the brush leaves the pan, said printing roller engaging the pan during the part of its movement, means for supporting an object to be printed in the path of the printing roller and means for rotating the roller during its reciprocatory movement, such means comprising a drum connected with the printing roller and having a spiral groove in its circumference and the cable having a part looped around the drum with its ends connected to a part of the frame.
4. A device of the class described comprising a frame including a pair of horizontally

arranged bars, a pair of members slidably arranged on the bars, a brush carried by one member, a printing drum carried by the other member, a pan of channel shape supported in the frame with the bottom of which the brush and printing roller are adapted to contact, a tank at the rear end of the pan, a perforated dipper in the pan, means for normally holding the dipper above the liquid level of the tank, a flexible member connecting a part of the dipper with the brush carrier whereby the dipper will be lowered when the brush carrier is moved over the pan, a lever connected to each of the sliding members, each connection being a slotted one, a link connecting the levers together, power means connected with one lever and imparting an oscillatory movement to the levers and a sliding movement to the brush and printing roller carrying means, said parts being arranged to cause the brush to pass back and forth over the pan and the roller to move over the pan to position beyond the pan, means for supporting a crate in the path of the roller and means for imparting the rotary movement to the roller as it is reciprocated.

5. A device of the class described comprising a frame including a pair of horizontally arranged bars, a pair of members slidably arranged on the bars, a brush carried by one member, a printing drum carried by the other member, a pan of channel shape supported in the frame with the bottom of which the brush and printing roller are adapted to contact, a tank at the rear end of the pan, a perforated dipper in the pan, means for normally holding the dipper above the liquid level of the tank, a flexible member connecting a part of the dipper with the brush carrier whereby the dipper will be lowered when the brush carrier is moved over the pan, a lever connected to each of the sliding members, each connection being a slotted one, a link connecting the levers together, power means connected with one lever and imparting an oscillatory movement to the levers and a sliding movement to the brush and printing roller carrying means, said parts being arranged to cause the brush to pass back and forth over the pan and the roller to move over the pan to position beyond the pan, means for supporting a crate in the path of the roller, means for imparting the rotary movement to the roller as it is reciprocated, said roller having a cushion under each type carried means and the guiding bars being supported for upward yielding movement.

In testimony whereof I affix my signature.
FRANK E. FOWLER.
